UNITED STATES PATENT OFFICE.

AMOS B. WEAVER, OF FLATWILLOW, MONTANA.

MOTOR.

1,286,853.

Specification of Letters Patent.

Patented Dec. 3, 1918.

Application filed April 24, 1918. Serial No. 230,456.

To all whom it may concern:

Be it known that I, AMOS B. WEAVER, a citizen of the United States, residing at Flatwillow, in the county of Fergus and State of Montana, have invented certain new and useful Improvements in Motors, of which the following is a specification, reference being had to the accompanying drawings.

- 10 This invention relates to certain improvements in motors and has relation more particularly to a device of this general character of a wind driven type and it is an object of the invention to provide a novel and improved device of this general character wherein the driving element includes feathered wings or vanes and a governor control whereby the rotation of the driving element is regulated.
- 20 It is also an object of the invention to provide a novel and improved motor of this general type wherein the power transmission shaft is directly and positively secured to the hub of the driving element for rotation therewith.

Another object of the invention is to provide a motor of this general character having novel and improved means whereby the rotation of the driving element is regulated by a governor mechanism.

The invention consists in the details of construction and in the combination and arrangement of the several parts of my improved motor whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

45 Figure 1 is a view partly in elevation and partly in section of a motor constructed in accordance with an embodiment of my invention;

50 Fig. 2 is a horizontal sectional view taken through the upper portion of the motor as illustrated in Fig. 1;

Fig. 3 is an enlarged fragmentary view partly in section and partly in elevation illustrating certain of the planes as embodied in a vane or wing in closed relation;

55 Fig. 4 is an enlarged view in plan of one

of the plates employed in the controlling mechanism for the driven element; and

Fig. 5 is an enlarged view partly in plan and partly in section of the plate employed 60 in the controlling means for the driven element and to which the core as herein employed is connected.

As disclosed in the accompanying drawings, T denotes a tower of any desired configuration and which is provided at its top with the crown or plate C. Secured to the crown or top plate C is a frame F. The frame F comprises the diametrically opposed horizontal arms 1 secured at their inner ends to the crown or plate C and the outer ends of the arms 1 are continued by the upstanding and perpendicularly related arms 2. The upper ends of the arms 2 are connected by the top cross members 3 substantially in the form of an inverted V. The opposite end portions of the arms 2 are also connected by the annular members 4. Suitably engaged with the frame F are the guy lines 5 whereby the frame F is 75 effectively maintained in applied position.

D denotes the driven member in its entirety and said driven member comprises the vertically disposed hollow hub H extending through the crown or top plate C. 85 The lower portion of the hub H is provided with the outstanding annular member or flange 6 overlying the crown or top plate C and affording a support for the hub H. Interposed between the crown or top plate 90 C and the hub H are the anti-friction members 7 whereby the hub H is permitted to rotate with the minimum of frictional resistance.

Radiating from the flange 6 are the arms 8 95 having their outer extremities continued by the upstanding arms 9. The upper end portions of the arms 9 are continued by the inwardly directed arms 10. The arms 10 constitute a spider and the central portion 11 100 of said spider is suitably affixed to the upper end portion of the elongated core or member 12 extending within the hub H through the top or upper end. The core or member 12 has its upper end portion rotatably engaged as at 14 with the apex portions of the arms 3. It may be stated at this time that the arms 3 also constitute a spider.

Each set of arms 8, 9 and 10 constitute a 110 wing or vane and arranged in vertical alignment within each of said wings or vanes is

a plurality of planes P. Each of said planes P is mounted for swinging movement about a horizontal axis.

The axis of each of the planes comprises 5 a shaft 15 having its opposite end portions rotatably supported by an arm 9 and the hub H. The end portion of the shaft 15 engaged with the hub H extends within the hub and terminates in the angularly disposed extension 16.

The planes P are adapted to assume a closed position by gravity, and the upper planes P of each series overlie the planes immediately therebelow so that the element D will be caused to rotate under the influence 15 of the wind. When the planes begin to move against the wind they will assume an open position so that the rotation of the element D will not be materially retarded.

I find it of advantage to provide the overlying portions of the planes P with the 20 expandable members or coil springs 17 in order to substantially eliminate rattling of the planes when in closed relation.

Secured directly to the lower portion of 25 the hub H is the vertically disposed tubular transmission shaft S having its lower end portion operatively connected as at 18 with the driven shaft 19.

Disposed upwardly through the shaft S is 30 a rod 20. The upper end of the rod 20 extends within the hub H and secured to the upper end of the rod 20 is a disk 21 provided in its marginal portion with the openings 35 22. The openings 22 are radially aligned with the wings or vanes of the driven element and loosely disposed through the openings 22 are the vertically arranged operating arms 23. The lower end portions of the 40 arms 23 are secured to a disk 24 through which the rod 20 is loosely directed. The rods 23 are also freely disposed through the radial recesses 25 produced in the marginal portion of a disk 26 suitably affixed to the 45 lower end portion of the core or member 12. Surrounding each of the rods 23 and positioned between the disks 21 and 24 are the expandable springs 27 and also encircling each of the rods 23 and positioned between the disks 21 and 26 are the expandable 50 springs 28.

Each of the rods 23 is provided with a series of longitudinally spaced dogs or contact members 29 equal in number to the 55 shafts 15 and each of said dogs 29 overlies an extension 16 of a shaft so that upon imparting downward movement to the shaft 23 the gravity or closing movement of the planes P may be limited so that said planes 60 may be entirely prevented from moving into closed position and may be caused to partly close to any desired degree or extent as the requirements of practice may necessitate.

The upper end portion of each of the rods 65 23 is pivotally engaged as at 30 with

a centrifugal governor arm 31 radiating from the upper portion of the core or member 12 and pivotally engaged therewith for movement in a vertical plane. Interposed between the outer end portion of 70 the arm 31 and the core or member 12 is a retractile member 32 which constantly urges the outer end portion of the arm 31 upwardly.

The lower end portion of the rod 20 is 75 pivotally engaged as at 33 with the lever 34 mounted for swinging movement in a vertical plane and said lever 34 is provided with a conventional latch mechanism 35 engageable with a rack 36 suitably positioned relative to the lever 34 so that the rod 20 may be held or locked in different vertical positions.

As the element D rotates the arms 31 have a natural tendency to swing outwardly and downwardly which results in a downward movement of the rods 23 resulting in a coaction between the dogs or stops 29 and the extensions 16 of the shafts 15 to control the closing movement of the planes P so that the element D will rotate at substantially the 90 same speed irrespective of the travel of the wind. The action of the arms 31 may be regulated by imparting upward movement to the rod 20. Upon imparting upward movement to the rod 20 the tension on the springs 27 is released whereby the rate of travel of the element D may be correspondingly increased as the governor arms 31 will raise the rods 23 whereby the planes P will drop farther toward the vertical. By moving the 100 rod 20 downwardly the springs 27 will be compressed and continued pull upon the rod 20 will result in pulling the rods 23 downwardly into engagement with the extensions 105 16 of the shafts 15 to lock the planes P at their limit of upward or substantially horizontal movement so that the element D will be caused to remain stationary.

The opposite ends of the arms 9 of the driven shaft are connected by the annular members 36 whereby the wings or vanes are maintained in the desired spaced relation.

From the foregoing description, it is thought to be obvious that a motor constructed in accordance with my invention is particularly well adapted for use by reason of the convenience and facility with which it may be assembled and operated and it will also be obvious that my invention is susceptible of some change and modification 115 without departing from the principles and spirit thereof and for this reason I do not wish to be understood as limiting myself to the precise arrangement and formation of the several parts herein shown in carrying out my invention in practice except as hereinafter claimed.

I claim:

1. A motor of the character described comprising a hub mounted for rotation around a 130

vertical axis, vanes radiating from the hub, each of said vanes including a series of planes movable about horizontal axes, adjacent planes overlying when in closed position, said planes assuming closed position by gravity, and means within the hub for controlling the gravity movement of the planes.

5 2. A motor of the character described comprising a hub mounted for rotation around a vertical axis, vanes radiating from the hub, each of said vanes including a series of planes movable about horizontal axes, adjacent planes overlying when in closed position, said planes assuming closed position by 10 gravity, and means within the hub operable under the influence of the rotation of the vanes for controlling the gravity movement of the planes.

15 3. A motor of the character described comprising a hub mounted for rotation around a vertical axis, vanes radiating from the hub, each of said vanes including a series of planes movable about horizontal axes, adjacent planes overlying when in closed position, said planes assuming closed position by 20 gravity, and means within the hub under centrifugal control for limiting the gravity movement of the planes.

25 4. A motor of the character described comprising a hub mounted for rotation around a vertical axis, vanes radiating from the hub, each of said vanes including a series of planes movable about horizontal axes, adjacent planes overlying when in closed position, said planes assuming closed position by 30 gravity, means within the hub under centrifugal control for limiting the gravity movement of the planes, and mechanically operated means coacting with the centrifugal means for also limiting the gravity movement of the planes.

35 5. A motor of the class described consisting of a hollow hub, wings radiating therefrom, each of said wings including planes, each of said planes being movable about an axis substantially at right-angles to the axis of the hub, said planes being freely movable in one direction, and centrifugally operated means arranged within the hub for controlling the movement of the planes in the opposite direction.

40 6. A motor of the class described comprising a hollow hub supported for rotation about a vertical axis, wings radiating from the hub, each of said wings including a series of planes mounted for swinging movement, each of said planes including a supporting member extending within the hub, and centrifugally operated means within the hub coacting with said supporting member for controlling the swinging movement of the planes in one direction.

45 7. A motor of the class described comprising a hollow hub supported for rotation about a vertical axis, wings radiating from the hub, each of said wings including a series of planes mounted for swinging movement, each of said planes including a supporting member extending within the hub, said supporting member within the hub being provided with an angular extension, an endwise movable rod within the hub provided with an abutment overlying the extension and adapted to contact therewith, a centrifugally operated means for moving the 50 rod in a direction to cause the abutment of the rod to engage the angular extension of the supporting member of the plane.

75 8. A motor of the class described comprising a hollow hub supported for rotation about a vertical axis, wings radiating from the hub, each of said wings including a series of planes mounted for swinging movement, each of said planes including a supporting member extending within the hub, said supporting member within the hub being provided with an angular extension, an endwise movable rod within the hub provided with an abutment overlying the extension and adapted to contact therewith, a 80 centrifugally operated means for moving the rod in a direction to cause the abutment of the rod to engage the angular extension of the supporting member of the plane, and mechanically operated means also coacting 85 with the rod for moving the same.

90 9. A motor of the class described comprising a hollow hub supported for rotation about a vertical axis, wings radiating from the hub, each of said wings including a series of planes mounted for swinging movement, each of said planes including a supporting member extending within the hub, said supporting member within the hub being provided with an angular extension, an 95 endwise movable rod within the hub provided with an abutment overlying the extension and adapted to contact therewith, a centrifugally operated means for moving the rod in a direction to cause the abutment of the rod to engage the angular extension of the supporting member of the plane, mechanically operated means also coacting 100 with the rod for moving the same.

105 In testimony whereof I hereunto affix my signature in the presence of two witnesses.

AMOS B. WEAVER.
